(57) CLAIM

The ornamental design for a shoe upper, as shown and described.

DESCRIPTION

FIG. 1 is a rear perspective view of a shoe upper showing our new design;

FIG. 2 is a rear view thereof;

FIG. 3 is a first side view thereof; and,

FIG. 4 is an opposite side view thereof.

The broken lines showing the remainder of the shoe are for environmental purposes only and form no part of the claimed design.
